UNITED STATES PATENT OFFICE.

MARTIN CHRISTENSEN, OF RACINE, WISCONSIN.

SIGNATURE-HANDLING DEVICE.

1,236,909.

Specification of Letters Patent. Patented Aug. 14, 1917.

Application filed February 23, 1917. Serial No. 150,472.

To all whom it may concern:

Be it known that I, MARTIN CHRISTENSEN, a citizen of the United States, and resident of Racine, in the county of Racine and State 5 of Wisconsin, have invented new and useful Improvements in Signature-Handling Devices, of which the following is a description, reference being had to the accompanying drawings, which are a part of this specification.

The invention relates to signature handling devices.

In the making of books, pamphlets, magazines, etc., it is common practice to insert 15 or superimpose a signature or group of signatures upon a signature or group of signatures moving along the saddle to the stitching mechanism and alining the signatures thus assembled previous to stitching them. To accomplish this purpose I have 20 previously used in connection with the main signature conveying mechanism an auxiliary saddle or support above this main conveyer upon which the signature or signatures 25 to be added to those moving along the saddle have been placed and from which they are removed by pins on the conveyer and superimposed, alined and moved along with the signature or signatures on the main 30 conveyer but considerable difficulty has been experienced with this form of device owing to the fact that the depending portion or portions of the signature or signatures to be superimposed were not spaced away from the moving signature so that they would get 35 in the way of the moving signature and thus prevent proper operation of the machine. To obviate this difficulty it is the object of the present invention to provide a supporting means for holding the signatures including the depending portion or portions 40 of the signatures to be superimposed and inserted away from the main conveyer and the signatures disposed thereon so that there 45 will be no interference between the two sets of signatures with the result that the signatures may be inserted or superimposed in a more efficient manner than has heretofore been possible.

50 The present device is designed to be used in connection with signature machines of the saddle type and the main conveyers and saddle may be of the type shown in my Patent No. 937,925, granted October 26, 1909,

or that shown in my Patent No. 1,140,734, 55 granted May 25, 1915.

The invention further consists in the several features hereinafter set forth and more particularly defined by claims at the conclusion hereof.

In the drawings:

Figure 1 is a plan view of the device showing it used with one of the types of conveyer above referred to;

Fig. 2 is a side view thereof;

Fig. 3 is a section taken on the line 3—3 of Fig. 1;

Fig. 4 is a section taken on the line 4—4 of Fig. 2;

Fig. 5 is a section taken on the line 5—5 70 of Fig. 2.

The type of conveyer shown in the drawings consists in brief of a movable saddle carried by a supporting frame 5. This saddle consists of a plurality of inverted V-shaped members 6 mounted on an endless chain 7 driven in any suitable manner by any suitable source of power, the upper run of the conveyer being guided by the plates 8 secured to the frame 5, said conveyer carrying pins 9 for engaging the signatures to move them along with the saddle. For a more detailed explanation of the operation and construction of this type of conveyer reference may be had to my prior Patent 85 No. 1,140,734, granted May 25, 1915. In my Patent No. 937,925 of October 26, 1909, is shown a form of conveyer consisting of a stationary inverted V-shaped saddle having a longitudinally extending slot or slots 90 therein through which pins carried by an endless chain project to move the signatures along the saddle and the present device may be used in connection with either of these types of conveyers or any suitable kind of 95 conveyer for a saddle stitch machine.

The present invention used in combination with the conveyer consists of means for superimposing a signature or signatures between the superimposed signatures and the 100 signatures on the conveyer.

So far as the means for holding the signature to be superimposed away from the conveyer whether for a single or double sheet the structure is the same in that this 105 supporting means consists of auxiliary saddle or support 14 or 14' mounted above the main saddle and supporting the upper por-

tion of the signature or signatures and supports 15 or support 15' for the depending portion or portions of the signature. The saddles are slightly inclined toward the conveyor and taper toward their delivery end. While I have shown the supports 15 and 15' separate from the supports 14 and 14' it will be obvious that so far as the broad idea of the invention is concerned that the supports 15 and 15' may be made integral with the saddle provision being made for allowing the pins on the conveyor to engage the signatures disposed on the supporting means above the conveyor.

15 In the specific form shown the saddles 14 and 14' and 15 and 15' are mounted on hangers consisting of rods 16 and brackets 17 mounted on a rod 18 carried by the frame 5 of the machine. The saddles 14 and 14' 20 are each provided with a collar bracket 19 fitting around the horizontally extending portion of its supporting rod 16 and angularly adjustably secured thereto by a set screw 20. The supports 15 and 15' each consist of an angled rod each vertically adjustably mounted in a collar 21 which collar is adjustably mounted for lengthwise and angular movement with respect to its supporting rod 16 to accommodate signatures of different lengths. The pins 9 carried by the conveyor are of a length to engage the rear edges of the signatures on either of the saddles above the main conveyor. With the construction thus far described it will be apparent that in each instance the supporting means serve to hold the superimposed signature or signatures including the depending portion thereof spaced away from the conveyor and the signatures disposed thereon so as to prevent any interference therewith and the signature-engaging means consisting of the pins 9 engage the rear edge or edges of the signature or signatures and move them off their supporting means and superpose them and aline them with the signatures on the main conveyor previous to the stitching operation.

However, as previously stated, the invention also provides for inserting a sheet between the sheets on the conveyor and the superimposed sheets. This is accomplished by making the saddle 14' of a length so that its delivery end is disposed between the saddle 14' and the conveyor and making the support 15' of a length to extend some distance beyond its coöperative saddle 14', Figs. 1, 2 and 3, the supports 15 and 15' serving to space the sheets carried thereby away from each other and from the conveyor.

60 With the parts thus arranged it will be apparent that when it is desired to insert a signature such as the sheet 10 between the signature 11 on the conveyor and the superimposed signature 12 on the saddle 14 this insert is placed on the saddle 14' in its first

position and that as the pin 9 carrying the signature 11 moves along it engages this sheet 10 moves it along until it runs under the saddle 14 where it is moved onto and alined with the sheet or signature 11 and that the pin 9 now moving both sheets 10 and 11 engages the sheet 12 moves it off its saddle and alines it with the signatures 10 and 11 previous to the stitching operation, the supporting means as previously described holding the various signatures spaced from each other so as to prevent interference.

It will be understood that in case a double page insert is to be handled another support 80 similar to the bar 15' but on the other side of the saddle 14' is used.

While for the purpose of clearness, one specific embodiment of the inventive idea has been herein shown and described, it is 85 apparent that the invention is not restricted to this particular construction but that the construction is capable of modification and change conforming to the definition given in the appended claims.

90 What I claim as my invention is:

1. The combination, with the saddle conveyor mechanism of a saddle stitch book-stitching machine, of supporting means disposed above said conveyor for supporting the signature and holding its depending portions spaced away from the conveyor, including a saddle; and signature-engaging means carried by said conveyor and removing the signature from said supporting 100 means onto the signatures carried by the conveyor.

2. The combination, with the saddle conveyor mechanism of a saddle stitch book-stitching machine, of supporting means disposed above said conveyor including a saddle for the upper portion of the signature and a support for maintaining the depending portions of the signature spaced away from the conveyor, and signature-engaging 110 means carried by said conveyor and removing the signature from said supporting means onto the signatures carried by the conveyor.

3. The combination, with the conveyor 115 mechanism of a saddle stitch book-stitching machine for conveying signatures to the stitching mechanism, of supporting means disposed above said conveyor comprising a saddle and supports extending down on both 120 sides of the saddle for holding signatures spaced away from the signatures on the conveyor, and signature-engaging means carried by the conveyor and removing the signatures from said supporting means onto 125 the signatures carried by the conveyor.

4. The combination, with the conveyor mechanism of a saddle type book-stitching machine for conveying signatures to the stitching mechanism, of signature support- 130

ing means comprising a main support, an auxiliary saddle mounted on said support above the conveyer, supports adjustably mounted on said main support and extending down on both sides of the saddle for holding the signature spaced away from the signatures on the conveyer, and signature-engaging means carried by the conveyer and removing the signature from said saddle and supports onto the signatures carried by the conveyer.

5. The combination, with the conveyer mechanism of a saddle type book-stitching machine for conveying signature to the stitching mechanism, of signature supporting means comprising a support for the upper portion of the signatures and supports on both sides of said support adjustable vertically and longitudinally with respect thereto for maintaining the depending portions of the signature spaced away from the conveyer and the signatures thereon, and signature-engaging means carried by the conveyer and removing the signature from said supporting means onto the signatures carried by the conveyer.

6. The combination, with the conveyer mechanism of a saddle type book-stitching machine for conveying signatures to the stitching mechanism, of supporting means disposed above said conveyer for supporting a signature and holding its depending portions spaced away from an insert and the conveyer, an inserter comprising supporting means having portions extending beneath said first mentioned supporting means for supporting an insert and holding its depending portion spaced away from the conveyer, and signature-engaging means car-

ried by the conveyer and removing the signatures from both of said supporting means onto the signatures carried by the conveyer.

7. The combination, with the conveyer mechanism of a saddle type book-stitching machine, of a superposed signature supporting means disposed above the conveyer comprising a saddle and supports extending down on both sides of the saddle for holding signatures spaced away from the signatures on the conveyer, insert supporting means disposed above the conveyer comprising a saddle extending to a position beneath the first named saddle and a support extending from its coöperative saddle to a position beneath said first named supporting means to hold the depending portion of the insert away from the conveyer, and signature-engaging means for removing the superposed signature and insert from their supports onto the signatures carried by the conveyer.

8. The combination, with the conveyer mechanism of a saddle type book-stitching machine, of supporting means above the conveyer for superposed signatures for supporting the folded portion and the depending portions thereof, supporting means above the conveyer for inserts for supporting the folded portion of the insert and the depending portion thereof, said insert supporting means extending for a portion of its length beneath said superposed signature supporting means, and signature-engaging means for removing the superposed signatures and inserts from their supporting means onto the signatures carried by the conveyer.

In testimony whereof, I affix my signature.

MARTIN CHRISTENSEN.
